No. 726,083.

PATENTED APR. 21, 1903.

H. B. MAYNARD.
NEEDLE THREADER FOR SEWING MACHINES.
APPLICATION FILED JUNE 12, 1902.

NO MODEL.

UNITED STATES PATENT OFFICE.

HAROLD B. MAYNARD, OF BROOKLYN, NEW YORK, ASSIGNOR TO HIMSELF
AND IVY HAWES, OF BROOKLYN, NEW YORK.

NEEDLE-THREADER FOR SEWING-MACHINES.

SPECIFICATION forming part of Letters Patent No. 726,083, dated April 21, 1903.

Application filed June 12, 1902. Serial No. 111,259. (No model.)

To all whom it may concern:

Be it known that I, HAROLD B. MAYNARD, a citizen of the United States, residing in the borough of Brooklyn, in the county of Kings, city and State of New York, have invented an Improvement in Needle-Threader Attachments for Sewing-Machines, of which the following is a specification.

My invention relates to attachments to the needle-bar of a sewing-machine by means of which the needle can be readily threaded without any special care or effort on the part of the operator and which device after use can be turned up out of the way of the movements of the needle. I provide a device for engaging the needle-bar of the sewing-machine and a rocker-bar supported by said device, the ends of which are preferably threaded and provided with perforations and nuts. A yoke-frame, preferably formed of wire, is received in the perforations of said rocker-bar and is clamped by said nuts, and this yoke-frame is provided with a foot-piece at right angles to the main depending or vertical portion of said yoke-frame, and this foot-piece is formed at the bend of the wire constituting the frame, and it serves as a point of attachment for a conical guide, that is divided and provided with curved meeting edges.

The device engaging the needle-bar I prefer to comprise a clip surrounding the bar and having a clamping-screw and a bracket extension connected therewith for supporting the rocker-bar; but the precise construction of the device is controlled by the shape of the needle-bar. The upright members of the yoke-frame are separated appreciably and at a distance which substantially agrees with the thickness of the sewing-machine needle, so that when the parts are in the threading position the needle is received between these parts of the frame, and said frame is to be adjusted when first placed upon the machine so that the small aperture in the conical guide comes directly opposite to the eye of the needle, and when the parts are in this position the thread passed through the guide also passes through the eye of the needle with the further movement thereof. The divided feature of the conical guide provides for the escape or the passing out of the guide of the thread when the yoke-frame is turned from a

depending operating position to an elevated position, where the same is temporarily out of use.

In the drawings, Figure 1 is a sectional side elevation representing my improvement. Fig. 2 is a front elevation that is at right angles to Fig. 1. Fig. 3 is a sectional plan at xx of Fig. 1. Fig. 4 is a sectional plan at yy of Fig. 2, and Fig. 5 is a sectional plan representing a modification on approximately the line xx of Fig. 1.

The band a and clamp-screw 1 form a clip device for engaging the needle-bar b . This bar b is of circular form in cross-section, and therefore the band a conforms thereto. c represents a bracket extension in the form of a bent plate of metal secured to the band a by a screw. The free ends of the bracket extension c are perforated to receive a rocker-bar d . This bar d is provided with threaded ends and adjacent perforations 23, and nuts 45 screw upon the threaded ends.

I provide a frame e , of wire, generally in the form of a yoke and having a foot-piece e' , formed by the bend of the wire, which foot-piece is at right angles to the yoke-shaped portions of the frame, while the upper portions are bent at right angles first in one direction and then in the other direction at the extreme ends of the frame, and these extreme ends pass through the perforations 23 of the rocker-bar d , and the nuts 45 bear against these ends of the yoke-frame e and force the same against the outer faces of the bracket extension c . In this manner the yoke-frame is firmly and rigidly held to the rocker-bar, and sufficient friction is thus produced to maintain the yoke-frame in any position in which the same may be placed. This structure also provides for an adjustability of the yoke-frame vertically in its relation to the rocker-bar d , because by simply loosening the nuts 45 the free ends of the yoke-frame may be moved in the perforations of the rocker-bar to a limited extent which is sufficient, however, to provide for slight differences in the lengths of sewing-machine needles, so that when the attaching device is once connected to the needle-bar this part need not be shifted, the adjustment being effected by moving the yoke-frame e .

Secured to the foot-piece e' of the yoke-

frame is a conical guide *f*, of sheet metal, the edges of which are curved and brought around in forming the conical guide, so that they approximately meet. The end of the conical

5 guide of smallest aperture is placed next to the uprights of the yoke-frame and the end of largest aperture at the free end of the foot-piece—or, in other words, at the bend of the wire forming the yoke-frame.

10 From Figs. 2 and 4 it will be noticed that there are parts of the yoke-frame extending from the foot-piece *e* upward that are approximately parallel and that occupy an adjacent position to one another, the same being separated to an extent about equal to the thickness of the sewing-machine needle, so that when the yoke-frame is in a depending position, as shown in Figs. 1 and 2 by full lines, the sewing-machine needle comes between the

15 parts thereof and against the small apertured end of the conical guide. The thread to be passed through the eye of the needle is straightened by the fingers and passed into and through the conical guide, and as the 25 same emerges from the small apertured end the thread passes directly through the eye of the needle owing to the accuracy of adjustment and the relation of the parts.

The dotted line *g*, Fig. 1, represents the 30 thread as having been passed through the guide and the needle, and in Fig. 1 the yoke-frame is shown by dotted lines in its elevated position, where the same is out of use. The object of dividing the conical guide is to provide an escape or means for the removal of 35 the thread from the guide when the yoke-frame is turned up into its elevated position, as otherwise the thread could not escape. In this movement the thread passes between the 40 curved meeting edges of the conical guide and slightly forces the same apart as it passes through.

In the modification, Fig. 5, I have represented the needle-bar *b'* of the sewing-machine as of rectangular form in cross-section, and because some of the needle-bars of sewing-machines are of this form it is necessary that a device be provided adapted for connection therewith to support the main features of the needle-threader attachment. In connection with this needle-bar of rectangular form I provide a bracket *c'*, passing around three sides of said needle-bar and receiving the stem of a clamping-nut *6*, the same passing 55 through the needle-bar and bracket, with the nut of the clamping device bearing against the bracket to hold the same to the rectangular needle-bar. This bracket *c'* is adapted to receive and support the rocker-bar *d* and 60 other devices going to make up the needle-threader attachment.

This device is exceedingly simple in its construction and is efficient in operation and after effecting the threading of the needle is 65 readily moved up out of the way, so that it does not interfere with the operations of the needle or needle-bar in sewing.

I claim as my invention—

1. A needle-threader attachment for sewing-machines, comprising a clamping device 70 for engaging the needle-bar, a rocker-bar supported thereby and movable therein, a yoke-frame having a foot-piece at the bend of the wire forming the same and which foot-piece is at right angles to the main portion, and a 75 divided conical guide having curved meeting edges with the larger apertured end of the conical guide at the bent end of the foot-piece and the smaller apertured end set at the junction of the foot-piece with the main 80 part of the yoke-frame, and means for connecting the free ends of the yoke-frame to the rocker-bar adjustably and for securing the same in position, said yoke-frame being adapted to swing with the conical guide in 85 its relation to the clamping device, substantially as set forth.

2. A needle-threader attachment for sewing-machines, comprising a clamping device engaging the needle-bar, a bracket extension 90 secured thereto and carried thereby and having apertures at the free ends thereof, a rocker-bar passing through the apertures of the bracket extension and having threaded ends and adjacent perforations, and nuts upon the 95 threaded ends of the rocker-bar, and a yoke-frame of wire having its free ends received in the perforations of the rocker-bar and secured thereto by said nuts, and a conical guide for the thread connected to and supported by the yoke-frame, substantially as set forth.

3. A needle-threader attachment for sewing-machines, comprising a clamping device engaging the needle-bar, a bracket extension 105 secured thereto and carried thereby and having apertures at the free ends thereof, a rocker-bar passing through the apertures of the bracket extension and having threaded ends and adjacent perforations and nuts upon the 110 threaded ends of the rocker-bar, and a frame of wire having a foot-piece at the bent portion of the wire which is at right angles to the main portion, and a main portion where the wires are in part parallel to one another 115 and in part diverging as a yoke with the ends of the wire bent at right angles to the yoke portion and again at right angles into short ends and the short ends passed through the 120 perforations of the rocker-bar and held adjustably therein by the nuts, and a conical guide formed of bent-up sheet metal divided and having curved meeting edges with the 125 small apertured ends of the conical guide set up to and at the spaced-apart parallel portions of the frame secured to the foot-piece, and with the large apertured end at the bend of the wire and free end of the foot-piece, substantially as set forth.

Signed by me this 10th day of June, 1902. 130
HAROLD B. MAYNARD.
